Primary Examiner — Bao-Yen T Nguyen*Assistant Examiner* — Loryn K. LeBlanc(74) *Attorney, Agent, or Firm* — Jose Cherson Weissbrot(57) **CLAIM**

The ornamental design for a light for photography, as shown and described.

DESCRIPTION

FIG. 1 is a perspective view of a light for photography showing my new design;

FIG. 2 is another perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a bottom plan view thereof;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2; and,

FIG. 13 is a partial enlarged view of FIG. 2.

The dash-dash broken lines in the figures are for the purposes of illustrating portions of the light for photography, which form no part of the claimed design. The additional

(Continued)

broken lines seen in FIGS. 1-2 and FIGS. 8-13 are for the purpose of disclosing enlarged views which form no part of the claimed design.
